SLINGSHOT

John H. Welch, Van Nuys, Calif.

Application November 3, 1958, Serial No. 53,259

Term of patent 7 years

(Cl. D34—15)

Figure 1 is a view in perspective as viewed from the front and right side of a slingshot embodying my new design;

Figure 2 is an enlarged sectional view taken on line 2—2 of Figure 1; and

Figure 3 is a side elevation of the slingshot.

Ornamental design is the same on the rear face of same.

The characteristic features of my design are shown by full lines in the drawing.

I claim:

The ornamental design for a slingshot, as shown and described.
